UNITED STATES PATENT OFFICE.

JOSEPH A. WALSH, OF WEST NEW YORK, NEW JERSEY.

LIQUID-DISPENSER.

1,311,628.

Specification of Letters Patent. Patented July 29, 1919.

Application filed June 16, 1919. Serial No. 304,474.

To all whom it may concern:

Be it known that I, JOSEPH A. WALSH, a citizen of the United States, and resident of West New York, in the county of Hudson 5 and State of New Jersey, have invented certain new and useful Improvements in Liquid-Dispensers, of which the following is a specification.

The object of my invention is to provide 10 a simple, cheap and efficient liquid dispenser, such as adapted for dispensing liquid soap.

My invention comprises a container, which may be in the form of a bottle having a suitable discharge nozzle, a band secured 15 around the container, and a supporting frame therefor having spaced arms with in-turned ends pivotally connected with such band on opposite sides of the container, and the latter is provided on opposite sides with 20 dents in its surface opposing the in-turned ends of the supporting frame. By preference such in-turned ends of the frame are riveted or headed over the inner surface of the band and enter the dents in the container whereby the latter may be partially 25 rotatively supported upon the headed ends of the frame arms and the container is kept from rotating axially therein.

My invention comprises novel details of 30 improvement that will be more fully herein-after set forth and then pointed out in the claims.

Reference is to be had to the accompanying drawings forming part hereof, in which 35 Figure 1 is a perspective view of a liquid dispenser embodying my invention;

Fig. 2 is a cross section on the line 2—2 in Fig. 1;

Fig. 3 is an enlarged detail section on the 40 line 3—3 in Fig. 1, and

Fig. 4 is a detail exterior view of a portion of the container looking from the left in Fig. 3.

Similar numerals of reference indicate 45 corresponding parts in the several views.

A container indicated at 1 may be in the 50 nature of a bottle of any suitable shape and dimensions, shown having a neck 1^a provided with a delivery nozzle 2 which may be in the form of an ordinary stopper having 55 an outlet orifice 2^a. At 3 is a band, which may be of suitable metal, fitted around the container. The band is shown provided with projecting ends 3^a which may be clamped together by screw or bolt 4^a to

securely retain the band around the container. The container is shown provided with an annular groove 5 in which the band 3 is fastened. A supporting frame or bracket is indicated at 6 shown in the form 60 of a wire bent to provide the loop portion 6^a and the spaced, outwardly projecting, substantially parallel arms 6^b. The arms 6^b are at substantially right angles to the loop portion 6^a, whereby the latter may be 65 fitted against a wall or other support and retained by a screw passing through the loop so that arms 6^b extend forwardly to support the container pivotally. The outer free ends of the arms 6^b straddle the container and are bent or extended inwardly to 70 form inturned projections 6^c. Said projections extend toward band 3 and pass respectively through opposing holes 7 in the band, whereby the latter is swiveled upon the projections 6^c. The inner ends of the inturned 75 projections 6^c after being passed through holes 7 of the band 3 are riveted over or headed at 8, whereby the arms 6^b are permanently retained pivotally supporting 80 band 3. The wall of the container 3 on opposite sides, opposing the headed end portions 8 of supporting arms 6^b, is dented at 9 to receive the riveted or headed portions 8 extending inwardly from band 3. The 85 dents 9 may be formed in the container, either of glass or other suitable material, when the same is molded, pressed, or blown to shape. The dents 9 in the wall of the container are adapted to coöperate in the 90 pivotal support of the container upon arms 6^b, and also serve to prevent the container from rotating axially within the band, hence, the latter is not required to be exceptionally tightly fastened around the container. 95

When the bracket is supported as before stated the container will hang therefrom, as illustrated, with the stopper 2 extending upwardly. When it is desired to dispense the liquid contents the container may be tilted or turned upside down so that the liquid will run out of the nozzle, and when the container is released it will automatically return to the hanging position as shown. The dispenser is cheap to manufacture, 100 thereby enabling it to be sold with liquid soap therein, is not liable to get out of order, and the parts are not likely to become broken or detached. 105

Having thus described my invention, 110

what I claim and desire to secure by Letters Patent is:—

1. A soap dispenser comprising a container having dents in its exterior, a band secured around the container over the dents, and a supporting frame having arms provided with end portions pivotally connected with the band and headed on the inner surface thereof opposing said dents.
- 10 2. A soap dispenser comprising a container having an external groove and dents in its wall on opposite sides within the groove, a band secured around the container within the groove and provided with holes, a supporting frame having spaced arms on opposite sides of the container the free ends of the arms having inturned ends extending through the holes in the band and having the inner ends thereof headed along the inner face of the band, the headed portions extending into said dents.
- 15 3. A soap dispenser comprising a container, a band secured around the container, a supporting frame comprising a piece of

wire having a loop and spaced arms extending therefrom at an angle thereto, said arms having inwardly extending portions at their free ends, said band having holes pivotally receiving the said end portions, the latter being headed over the inner surface of the band.

25 4. A soap dispenser comprising a container, a band secured around the container, a supporting frame comprising a piece of wire having a loop and spaced arms extending therefrom at an angle thereto, said arms having inwardly extending portions at their free ends, said band having holes pivotally receiving the said end portions, the latter being headed over the inner surface of the band, said container having dents in its wall on opposite sides receiving said headed ends.

35 40 Signed at New York in the county of New York and State of New York this 13th day of June A. D. 1919.

45 JOSEPH A. WALSH.
